UNITED STATES PATENT OFFICE.

LAWRENCE SKOK, OF CLEVELAND, OHIO.

METAL CASING FOR LEAF-SPRINGS.

1,284,482.

Specification of Letters Patent. Patented Nov. 12, 1918.

Application filed December 20, 1917. Serial No. 208,023.

To all whom it may concern:

Be it known that I, LAWRENCE SKOK, having made application to become a citizen of the United States, and residing at Cleveland, in the county of Cuyahoga and State of Ohio, have invented a certain new and useful Improvement in Metal Casings for Leaf-Springs, of which the following is a full, clear, and exact description, reference 5 being had to the accompanying drawings.

This invention relates to a metal casing for laminated springs of a type adapted to closely embrace the spring and extend longitudinally thereof, to insure lubrication and 15 prevent waste thereof while protecting the spring from dust and dirt. The object of the present invention is to provide a casing which shall be simple in construction, economical of metal of which the casing is 20 made, and capable of being readily applied to the spring.

My invention is hereinafter more fully described in connection with the accompanying drawings. Other objects will become apparent in the description and the essential characteristics hereof are summarized in the claims.

In the drawings, Figure 1 is a plan of my casing applied to laminated springs; Fig. 2 is a side elevation of the same; Fig. 3 is an enlarged bottom plan of a portion thereof; Fig. 4 is a longitudinal central section through the casing; Fig. 5 is a transverse section through the casing as indicated by 35 the line 5—5 of Fig. 4; Fig. 6 is a section through the casing as indicated on the line 6—6 of Fig. 1; Fig. 7 is a transverse section through one of the intermediate elements of the casing; Fig. 8 is a bottom plan 40 of one of the elements removed; Fig. 9 is a similar plan of the binder for the end of the casing, shown in section in Fig. 6; Fig. 10 is a perspective view of a portion of the securing strip; Fig. 11 is a longitudinal sectional detail of the small end of the spring and casing.

Describing the parts by the use of reference characters, A indicates the long continuous leaf of the spring which may terminate in a horizontal portion at the end of the spring, after the manner of cantaliver springs, or may be provided with the usual eye or head B, indicated in broken lines in Fig. 2 for the reception of a spring bolt. 55 Other leaves of the spring B, C, D, E, and F may terminate at successively longer dis-

tances from the small end of the spring in the usual way, thus providing in effect a tapered curved spring.

The essential feature of the present invention is to inclose the portion of the spring, between the thicker portion where it is secured to an axle or frame member of the vehicle and the small end or eye of the spring, with a single thickness of the metal, 60 as far as possible, while still providing substantially oil-tight and dirt proof joints between the several sections of the casing, which are overlapped and jointed in such a fashion as to allow the flexing of the 65 spring with the least resistance and friction.

To this end I provide a series of sections or elements, designated 1, 2, 3, 4, 5, 6, 7, and 8, each embracing 4 sides of the spring. The member 1 is formed of a single piece of thin 70 sheet metal having a portion extending along the upper lamination of the spring, the full width thereof and integral with side members 10, extending across the edges of the laminations and having inwardly turned 75 edge portions bent into a position substantially parallel with the lower leaf A of the spring, and provided with outwardly turned flanges 12. The member 2 is similarly constructed having sides 10, extending across 80 the edges of the spring leaves and turned inwardly at 11 into substantially parallel relation with the leaf and also provided with separated outwardly turned flanges 12, as just described. Section 2 is so arranged 85 that it may project into the adjacent end of the member 1 and closely fit the same.

I prefer to provide a means tending to hold the sections from longitudinal separation by forming in the member 1, an outward dent or cavity 14 adapted to receive a corresponding hump 15 on the member 2. Each of the sections is fashioned similarly to the section 2 described except the last section which is provided with no fastening 90 hump into which the next member may spring. Each of the sections is cut so that when bent into position and placed over the spring, it may embrace the same closely and conform to its taper.

As a suitable flexible means for securing the sections into position, I have shown a band or strip 20 having inwardly turned flanges 22 embracing the flanges 12 of all of the sections and extending continuously 100 along the under side of the spring. The flanges 12 form in effect integral extensions

of the portions 11 of each section, and are bent abruptly outwardly and back upon themselves. To permit the telescoping of one section into the next adjacent section, 5 the flanges are made somewhat shorter than the body section, as illustrated in Figs. 4 and 8. The flanges are separated a sufficient distance from the surface of the portions 11 so that the flanges 22 of the strip 20 may be 10 readily thrust into engagement with the flanges 12 of the successive sections, even though the telescoping tends to bring the flanges 12 slightly out of longitudinal alinement by reason of the thickness of the metal 15 of the portions 11, as is clearly apparent from the section, Fig. 4.

The end section 1 may be secured tightly around the spring by a suitable U-shaped clamp 30 having a bolt 31 extending through 20 ends overhanging the lower side of the spring. At 35 is a similar U-shaped clamp having its bolt 36 extending through the overhanging ends of the clamp and tightly fitting against the strip 20 in such a fashion 25 that it may serve the usual purpose of preventing a separation of the leaves, thus preventing too great a strain on the casing sections. To bind the end section 8 closely about the spring and avoid a cumbersome 30 unsightly binder, I prefer to use a band substantially of the same material as the metal of the several sections. Such a band is illustrated at 25 as an intermediate section lying across the top portion of the section 8 and 35 extends closely across the sides of the portion and is bent into close engagement with the bottom or lower sides of the section 8, the flanges 12 of the section being removed at this point, whereby flanges 26 on this section 40 may engage the flanges 22 of the strip 20.

I prefer to assemble this spring by bending the sections into substantially the shape illustrated in Fig. 7 with the lower parts 11 in position shown in broken lines so that the 45 sections may be readily sprung over the spring and thus assembled one by one, bending the flaps 11 inwardly and securing them by advancing the strip 20 longitudinally to engage the flanges 12 of each section as it is applied. A strip 40, substantially the width 50 of the spring, may extend along the under side of the spring, if desired, while a similar strip, indicated at 42 (Fig. 5) may extend along the upper part of the spring, thus insuring 55 the closing of the joints. While either or both of these strips may be omitted, the upper strip 42 is particularly desirable, in that it bridges across and overlaps shoulders formed by the successively shorter ends 60 of the laminations A, B, C, D, E and F.

When the spring is assembled I may provide one of the sections, as at 3, with a suitable lubricant cup indicated at 45, threaded or soldered into a boss formed on this section 65 at 46 and registering with a corresponding

opening in the strip 42 so that lubricant may be led into immediate contact with the spring and may find its way throughout the length of this casing and into the spring between the laminations. To prevent the escape of 70 lubricant, particularly when a fluid lubricant is used, it is only necessary to make the U-clamp 30 and the bolt 31 form a substantially tight joint which I may insure by providing a packing of cloth or any other material under this clamp. To prevent the escape of 75 lubricant and the entrance of dirt at the smaller end of the casing, I may provide under the band 25 a packing indicated at 48 of several layers of cloth or other suitable 80 material.

In order that the humps and recesses, which prevent the several sections of the casing from shifting longitudinally and telescoping one on the other, allowing free flexing of the spring, I prefer to provide the raised recesses 14 somewhat larger in area than the humps or projections 15. Thus, as the spring flexes, a slight longitudinal movement between them may occur, the projections 15 sliding within the recesses 14 and allowing the shifting between the sections while still preventing one sliding entirely over the other and thus separating from the next adjacent section. It will be seen that consequent upon the flexing of the spring a sliding overlapping movement may occur at the upper portions of the sections, while the overlapping portions at the bottom may also slide one into the other allowing the required movement. 95

Having thus described my invention, what I claim is:

1. A casing for laminated springs comprising a plurality of sections made of thin sheet metal bent around the spring, the lateral edges of the sections being provided with flanges, and a flexible strip having coacting flanges extending longitudinally of the spring. 105

2. A casing for laminated springs comprising a plurality of sections made of thin sheet metal bent around the spring and having their lateral edges provided with flanges, a flexible strip having coacting flanges extending longitudinally of the spring, and means for preventing longitudinal displacement of the sections. 115

3. A casing for laminated springs comprising a plurality of sections made of thin sheet metal and comparatively short with relation to the length of the spring, said sections extending around the spring and having edges slightly separated at one side of the spring and provided with securing means, a sheet metal member extending longitudinally of the spring and coacting with said securing means to hold the sections closely embracing the spring, and coacting depressions and projections on each section 120 125 130

for preventing longitudinal displacement of the sections.

4. A casing for laminated springs comprising a plurality of sections made of thin sheet metal, extending around the spring, an outward depression on one section and a projection on the adjacent section coacting therewith for preventing longitudinal displacement, the depression being of such size
- 10 as to permit limited longitudinal movement consequent upon the flexing movement of the spring.
- 15 5. A casing for flexible metal springs comprising a plurality of short sections, embracing four sides of the spring and each section, save one, overlapping the next section in the series, on all sides of the spring, means for holding the sections in embracing position and forming with the sections
- 20 a closed tube, and means for preventing longitudinal displacement while allowing the relative flexing movement at the overlapping portions consequent upon the movement of the spring.
- 25 6. A casing for flexible laminated springs consisting of a plurality of sections arranged end to end and overlapping and having outwardly turned flanges extending longitudinally of the spring, the flanges on the several sections being in substantial alinement, and a member extending along the spring and engaging said flanges.
- 30 7. A casing for laminated springs consisting of a series of comparatively short

sections extending around three sides of the spring and with the edges thereof extending toward each other at the fourth side and provided with outwardly curved flanges, the flanges of the sections being in substantially longitudinal alinement, a flexible metal strip 40 extending along the spring and having inwardly turned flanges engaging the flanges on said sections.

8. A casing for laminated springs consisting of a plurality of sections extending 45 around and embracing four sides of the spring and having means securing them in their embracing positions, means holding one end section in close engagement with the spring, a short annulus of packing between the spring and the other end section, and means for injecting lubricant into the casing.

9. A metal casing for laminated springs consisting of a strip substantially the width 55 of the spring and lying along the spring at one side thereof, a plurality of sections of sheet metal, each section embracing four sides of the spring and said strip, means for holding the sections in position, means for 60 making a lubricant tight joint at each end of the casing and the spring, and means for injecting lubricant into the casing through one of said sections and through said strip.

In testimony whereof, I hereunto affix my 65 signature.

LAWRENCE SKOK.
